UNITED STATES PATENT OFFICE.

JOSHUA GREEN, OF HOVE, ENGLAND.

GRAMOPHONE.

Application filed November 24, 1920. Serial No. 426,213.

To all whom it may concern:

Be it known that I, JOSHUA GREEN, a subject of the King of Great Britain, residing at 38 Rutland Gardens, Hove, Sussex, England, have invented new and useful Improvements in Gramophones, of which the following is a specification.

This invention relates to horn gramophones of the kind which can be collapsed or dismembered to render them portable and particularly of the type wherein the stem of the horn or amplifier is detachable, and it has for its object the production of a gramophone which when collapsed, occupies a minimum of space and at the same time provides accommodation for a number of records.

According to my invention I form the mouth of the horn or amplifier so that it can be collapsed or caused to assume a flattened form and I arrange such horn mouth in conjunction with a plate or frame to which is hinged another plate or frame carrying the motor and tone arm so that these parts can be folded together.

In the accompanying drawing which illustrates a suitable arrangement for carrying the invention into practice.

Figure 1 is a sectional side view of the improved gramophone with its parts in position for use and with the back cover removed.

Figures 2 and 3 are, respectively, a front view and a plan view thereof.

Figure 4 is a sectional side view showing the parts of the gramophone collapsed, with the back cover in position and

Figures 5 and 6 are, respectively, front and rear views thereof with the cover removed.

a is the main frame of sheet-metal or other material in box form, open at the front and back ends which are designed to be closed by lids or covers *b*, *c* when the gramophone is collapsed, as shown in Figure 4, the front cover having a recess *b*¹, hereinafter referred to. The said frame has a partition *d* adjacent to its front end with a circular opening *d*¹ therein, around the edge of which is fixed a series of radiating strips *e* (preferably overlapping) of spring sheet-metal or other elastic material, which, when bent inwards, form the mouth of the gramophone horn or amplifier, as shown in Figures 1, 2 and 3. To the inner surface of the upper

part of the main frame is hinged at *f* an upper plate or frame *f*¹ to the underside of which is attached a suitable motor *g* having, by preference, a slip-on cover *g*¹, the said plate having an extension in the form of a bracket or tone arm support *h* to which is universally jointed, say, by a ball *j* and socket *j*¹, in the known manner, the tone-arm *i* carrying the sound-box *j*¹. The socket *j*¹ is made revolvable by an extension or pin *j*² thereon mounted in a bearing in a boss *j*³ on the bracket *h*, whereby the said tone-arm can be turned on its side when the gramophone is collapsed, as shown in Figures 4 and 6. A collar *k* is provided in sliding connection with the pin *j*², the said collar having a tooth *l* which is caused by a spring *l*¹, arranged between the said collar and a head on the said pin *j*², to engage notches *l*² in the boss *j*³ in the "in use" and "collapsed" positions of the said tone-arm. The upper plate *f*¹ is locked to the upper part of the main frame *a* when extended or raised in position for use, by suitable means, such as a spring-bolt *m*. Another plate *n* is hinged at *n*¹ to the inner surface of the base of the frame *a* and forms a rearward extension of the said base, the front lid or cover *b* being advantageously slid in between the outer end of the plate *n* and the outer end of the extension bracket or tone arm support *h*, to form a strut or tie between these parts, the said outer ends being correspondingly formed or recessed as shown, to receive it. *o* is the stem of the trumpet or horn, which stem is detachable and is designed to be connected by a bayonet joint *o*¹ (or other form of joint) to a short tube *p* on the bracket *h*. This tube *p* is in connection with the revolvable socket *j*¹ for the tone-arm, and the stem *o* when connected to the tube *p* holds the radiating spring strips *e* in their bent or trumpet mouth position as shown in Figure 1. *q* and *r* are, respectively, a speed regulator and brake of known construction which are carried upon the upper plate *f*¹ and project through openings *q*¹, *r*¹ in the top of the main frame *a* when in position for use, as shown in Figures 1, 2 and 3.

When the gramophone is to be collapsed to the position shown in Figure 4, the stem *o* of the horn or trumpet is first disconnected from the tube *p* on the revolvable

socket j^1 thus allowing the radiating spring strips e to assume the straight or flat form shown in Figures 4 and 5. The front cover b is then removed from between the extension bracket h and the plate n , and the turntable s , which is of known construction, is removed from the taper upper end of the driving spindle g^2 of the motor g and laid within the circular recess b^1 in the cover b hereinbefore referred to. The stem o is then placed within the box or main frame a in the position shown in Figure 6 and the spring bolt m retracted to allow the plate f^1 to be lowered on its hinge together with the tone-arm i into the said box, the said tone-arm, at the same time, being turned on its side so that the tooth l is forced out of one notch l^2 and snaps into the other notch l^2 . The winding key t can also be placed within the box a , as indicated in Figure 6. The plate n hinged to the base of the box or frame a is then turned up into a vertical position, as shown in Figure 4, so as to shut in the said lowered parts. The box or main frame a can then be engaged with the front cover b containing the turn table s , and a number of records u placed in the recess u^1 in the case a behind the turned-up plate n , the back cover c being then placed in position on the back of the said box. Finally, a pair of adjustable leather or other straps v having a carrying handle w is secured around the box and its covers, as indicated in Figures 4 and 5, rendering the gramophone in its collapsed condition and with its load of records capable of being easily carried.

In the drawing the recess u^1 is shown of a capacity sufficient for twelve records. By sliding the cover c backwards, however, to a position such, for instance, as that indicated in dotted lines Figure 4, a greater number of records can be enclosed and supported.

The back cover c can serve as a holder or store for the records when the machine is in use.

Having now particularly described and ascertained the nature of my said invention and in what manner the same is to be performed, I declare that what I claim is:

1. In a gramophone, the combination with the casing, provided with a tone arm support, of a tone arm, a universal joint therefor, comprising a member connected with the tone arm and a member pivotally connected with said tone arm support, whereby said tone arm and the members of said universal joint may be turned upon said pivotal connection into operative and inoperative positions.

2. In a gramophone, the combination with the casing, of a tone arm support hinged with respect to the casing, a tone arm, a universal joint comprising a member connected with

the tone arm and a member pivotally connected to said tone arm support, and capable of moving with the other member of the universal joint and the tone arm, with respect to the tone arm support, into and out of operative position, means for temporarily securing said tone arm support in operative relation with the casing, and means for temporarily securing said pivoted member of the universal joint in operative relation with respect to said tone arm support, whereby said tone arm and its universal joint may be turned into inoperative position with respect to said tone arm support and folded therewith within the casing.

3. In a gramophone, the combination with a casing, of a tone arm support hinged with respect to the casing, a tone arm, a universal joint comprising a member connected with the tone arm and a member pivotally connected to said tone arm support and capable of moving with the other member of the universal joint and the tone arm, with respect to said tone arm support into and out of operative position, means for temporarily securing said tone arm support in operative relation with the casing, means for temporarily securing said pivoted member of the universal joint in operative relation with respect to said tone arm support, and a motor rigidly connected to said tone arm support and adapted to fold therewith within the casing.

4. In a gramophone, the combination with a casing, provided with a vertically supported plate having a sound delivery aperture therein, a plurality of strips of resilient material having their outer ends secured to said plate around the edges of said aperture and adapted to normally lie flat in a plane substantially parallel with the plane of the plate, said strips having overlapping edge portions, said casing being provided with a folding hinged portion, and a tone arm carried thereby, and a detachable tubular member provided at one end with means for connecting it with the tone arm when the latter is in operative position, the opposite end of said tubular member being adapted to be detachably connected with and inserted within the free ends of said strips, whereby said tubular member may be detached to permit said strips to return to their flat, normal position, and to permit the hinged part carrying the tone arm to be folded.

5. In a gramophone, the combination with a casing provided with a vertically supported plate having a sound delivery aperture therein, a plurality of strips of resilient material having their outer ends secured to said plate around the edges of said aperture and adapted to normally lie flat in a plane substantially parallel with the plane of the plate, said strips having overlapping edge portions, said casing being provided with a

- 5 folding hinged portion, and a tone arm carried thereby, and a detachable tubular member provided at one end with means for connecting it with the tone arm when the latter is in operative position, the opposite end of said tubular member being adapted to be detachably connected with and inserted within the free ends of said strips, whereby said tubular member may be detached to 10 permit said strips to return to their flat, normal position, and to permit the hinged part carrying the tone arm to be folded, a detachable plate for engaging the casing and closing the sound delivery aperture when 15 the apparatus is in folded position, and means connected with the said hinged portion of the casing for engaging the said detachable plate and supporting the tone arm when the parts are in operative position.
- 20 6. In a gramophone, the combination with a casing provided with a vertically supported plate having a sound delivery aperture therein, a plurality of strips of resilient material having their outer ends secured to said plate around the edges of said aperture, and adapted to normally lie flat in a plane substantially parallel with the plane of the plate, said strips having overlapping edge portions, said casing being provided with a folding hinged portion, and a tone arm carried thereby, and a detachable tubular member provided at one end with means for connecting it with the tone arm when the latter is in operative 25 position, the opposite end of said tubular member being adapted to be detachably connected with and inserted within the free ends of said strips, whereby said tubular member may be detached to permit said strips to return to their flat, normal position, and to permit the hinged part carrying the tone arm to be folded, said casing having a folding member hinged to the bottom thereof and adapted to form an extension of the bottom of the casing, a detachable plate adapted to engage the casing and close the sound delivery aperture when the apparatus is in folded position, said folding member and said hinged member being provided with means for engaging said detachable plate to hold the hinged member and tone arm in operative position, said detachable plate being provided with a circular recess for receiving the turntable of the machine and holding it between it and the plate containing the sound delivery aperture.
- 30 7. In a gramophone, the combination with a casing, a hinged part secured to the casing and adapted to project therefrom in substantial alignment with a wall of the casing and forming a continuation thereof when in operative position, a motor secured to and carried by the said hinged part, a removable turntable therefor, a tone arm connected to the hinged part, and capable of folding with respect thereto, and also of folding therewith into the casing, a demountable horn member detachably connected with the tone arm, and means for supporting said hinged part in operative position.
- 35 8. In a gramophone, the combination with a casing, of a hinged part adapted to be folded with the casing, and to be projected outside of the casing, and means for supporting said hinged part in projected position, a motor secured to said hinged part and adapted to fold therewith into said casing, a tone arm, a universal joint for said tone arm comprising a member connected with the tone arm, and a member having a pivotal connection with the said hinged part, the axis of said pivotal connection extending longitudinally of said hinged part, means for detachably securing said pivoted member of the universal joint in position to hold the tone arm in operative position, whereby said tone arm and the members of the universal joint may be folded laterally with respect to said hinged part and folded therewith within the casing when not in use.
- 40 9. In a gramophone, the combination with a casing, of a hinged tone arm support adapted to be folded within the casing, and to be projected outside of the casing, and means for supporting said hinged part in projected position, a motor secured to said hinged part and adapted to fold therewith into the casing, a tone arm, a universal joint for said tone arm comprising two members one of which is connected with the tone arm, a pivot pin connecting the other member of the universal joint to the said hinged tone arm support, and a spring actuated locking collar on said pivot pin for engaging a part connected with the tone arm support to detachably secure the universal joint and tone arm in operative position whereby said tone arm and universal joint members can be folded on said pivot pin with respect to the said hinged tone arm support and folded therewith within said casing.
- 45 10. In a gramophone, the combination with a casing having its rear end open and provided with a hinged closing plate forming an extension of the lower side of the casing when in open position, a hinged tone arm support secured to the upper side of the casing and adapted to fold within the casing, and to form an extension of the upper side when in open position, a motor secured to the hinged tone arm support, a tone arm, a universal joint comprising two members, one of which is connected to the tone arm, and the other of which is pivotally secured to said hinged tone arm support, means for detachably securing said

pivoted member of the universal joint in position to hold the tone arm in operative position, a detachable turn table for the motor, said casing having a recess in its front face to hold the turn table when not in use, and a detachable cover for the front face of the casing to enclose the turn table, said

cover being adapted to engage the hinged closing plate and said hinged tone arm support to hold the latter, and the tone arm and motor in operative position when not in use. 10

JOSHUA GREEN.
